UNITED STATES PATENT OFFICE.

CARL GALITZ, OF SASSNITZ, GERMANY.

CHIMNEY ATTACHMENT.

No. 914,134.

Specification of Letters Patent.

Patented March 2, 1909.

Application filed November 6, 1908. Serial No. 461,401.

To all whom it may concern:

Be it known that I, CARL GALITZ, a subject of the Emperor of Germany, residing at Sassenitz a. Rügen, in the Empire of Germany, 5 have invented new and useful Improvements in Chimney Attachments, of which the following is a specification.

The invention relates to a chimney-attachment with a horizontally arranged vane-10 wheel.

In the chimney-attachments of this kind heretofore suggested, by reason of the arrangement of the vane-wheel, it has been inconvenient to look after the vane-wheel and 15 to clean the attachment. This disadvantage is obviated according to the present invention by mounting the vane-wheel on a door on the attachment. If the vane-wheel is to be inspected or the attachment cleaned, the 20 door is simply opened and the wheel swung out.

Heretofore the spindle of the vane-wheel has been allowed to run in two step or pivot-25 bearings, yet in this arrangement there was the disadvantage that the ascending soot was driven into the open upper bearing and the rotation of the pivot-journal on the spindle in this bearing was impeded.

According to the present invention, this 30 disadvantage is obviated in that, in the place of the upper step-bearing, a guide-pin or pivot is provided, which enters into a recess in the upper end of the spindle and in this manner guides the spindle.

The accompanying drawing shows one 35 constructional form of the new chimney-attachment, viz:

Figure 1 shows the same in vertical section, Fig. 2 in plan with the door closed, Fig. 40 3 in plan with the door opened. Fig. 4 shows the spindle-bearings drawn to an enlarged scale.

a is a tubular casing or pipe of the chim-

ney-attachment and *b* the door thereof; *c* is a bracket secured to this door, in which 45 bracket the horizontal vane-wheel *d* is mounted. *e* is the spindle of the vane-wheel, which runs at the bottom in a step-bearing *g* and at the top on a pivot *f* which enters into a recess in the spindle. In this 50 arrangement, the door *b* with the vane-wheel *d* can be swung outwards (Fig. 3), for the purpose of inspecting the vane-wheel *d* and cleaning the casing or pipe *a*. The soot driven upward by the air-current or draft 55 moves past the step-bearing *g* and the pivot-bearing *f* and is thus effectually prevented from penetrating into the bearings. The rotation of the spindle is consequently not impeded. 60

What I claim is:—

1. A chimney-attachment comprising a tubular casing having an aperture therein, a door mounted on said casing and adapted to close said aperture, and a vane-wheel rotatably mounted on said door. 65

2. A chimney-attachment comprising a pipe having an aperture therein, a door pivotally mounted on said pipe and adapted to close said aperture, a bracket on said door, a spindle rotatably mounted in said bracket, and a vane-wheel mounted on said spindle. 70

3. A chimney-attachment comprising a tubular casing having an aperture therein, a door mounted on said casing and adapted to close said aperture, a spindle, a vane-wheel mounted on said spindle, a pivot-pin mounted on said door and extending into a recess in the upper end of said spindle, and a step-bearing mounted on said door and receiving 75 the lower end of said spindle. 80

CARL GALITZ.
